UNITED STATES PATENT OFFICE.

HENRY ALEXIS WILLIAMS, OF QUINCY, MASSACHUSETTS, ASSIGNOR TO THE PUTNAM NAIL COMPANY, OF BOSTON, MASSACIUISETTS.

MACHINE FOR FORGING HORSESHOE-NAILS.

SPECIFICATION forming part of Letters Patent No. 651,586, dated June 12, 1900.

Application filed March 20, 1900. Serial No. 9,431. (No model.)

To all whom it may concern:

Be it known that I, HENRY ALEXIS WILLIAMS, a citizen of the United States, residing at Quincy, in the county of Norfolk and State 5 of Massachusetts, have invented certain Improvements in Machines for Forging Horseshoe-Nails and other Articles, of which the following is a specification.

This invention relates to an improvement 10 on the machine for forging horseshoe-nails and other articles for which Letters Patent of the United States, No. 625,229, were granted to me May 16, 1899; and my invention consists in certain improvements in the mechanism 15 by means of which the end of the blank or partly-finished nail which forms the head is placed at the proper moment within the recesses of the roller-dies, so that a head of the proper length and shape may be formed, 20 as desired. The device employed in the machine described in the aforesaid patent consists of a pair of cam-operated grippers which were secured to a slide and after seizing the blank or partly-finished nail carried it down 25 to its proper place in the dies. When, however, the rolls were revolving at a very high speed, these grippers were liable to slip and sometimes failed to carry the blank or partly-finished nail far enough into the dies to produce a head of the proper length. 30

To overcome this difficulty is the object of my present invention, which consists in the combination, with a pair of die-grooved rolls and a conducting tube or guideway, through 35 which the blanks or partly-finished nails pass to said rolls, of a sliding spring-pressed nail-pusher adapted to enter the conductor through a slot or opening in one of its walls after the blank has been dropped onto the 40 rolls beneath and bear on the upper end of the nail-blank with a spring-pressure sufficient to cause it to be instantly and fully forced down to the bottom of the dies the moment the latter are brought into a position to 45 receive it, thereby avoiding any possibility of the head of the blank or partly-finished nail failing to reach its proper position in the dies and insuring the formation of a head of the required length when the rolls are running at 50 a high speed, as hereinafter more fully described.

In the accompanying drawings, Figure 1 is a horizontal section of a nail-forging machine, showing a pair of its die-grooved rolls, the nail-conductor leading thereto, and my improved nail-pushing device for insuring the proper placing of the nail-blank within the dies of the rolls. Fig. 2 is a front elevation of a portion of the machine, showing my nail-pushing device applied thereto. Fig. 3 is an enlarged vertical section on the line 3 3 of Fig. 2. Fig. 4 is a perspective view of the nail-pusher-actuating mechanism and the nail-conducting tube leading from one pair of rolls to the next pair beneath. Fig. 5 is a horizontal section of one of the nail-conducting tubes, showing the nail-pusher within the same. Fig. 6 is a perspective view of the slide which carries the nail-pusher, showing in dotted lines the slide-actuating arm engaging a slot in the front of said slide. Fig. 7 is a similar view of the nail-pusher slide which is applied to the nail-conducting tube next beneath, showing in dotted lines the actuating-arm engaging a slot in the side of the slide, as is necessary, owing to the die-grooved rolls being arranged in pairs at right angles to each other. 55 60 65 70 75

In the said drawings, A represents the framework of the machine, of proper shape to support the working parts. 80

B B denote the die-grooved rolls of the machine, which are arranged in pairs beneath each other, the two rolls of a pair being connected to revolve together by gears 85 b b and each pair being arranged at right angles to the pair immediately above or below it in the same manner as shown and described in my aforesaid patent, No. 625,229. The rolls B B are supported in boxes 15, 90 mounted in housings C, secured to the vertical wall of the framework A. The journal of one roll of each pair is elongated and connected with a shaft 20 in line therewith by means of a coupling 21, and each of said 95 shafts 20 is provided with a gear 22, which meshes with another gear 23, receiving motion by means of shafts and gears from the driving-shaft of the machine.

D D represent the conducting-tubes, through 100 which the nail-blanks or partly-made nails pass from one pair of die-grooved rolls to the

pair next beneath. Each of the conducting-tubes D is provided on one side with a narrow longitudinal slot 25, enlarged at its upper end at 26, as shown in Figs. 2 and 4, for the entrance of the nail-pusher to be presently described. In suitable guide-grooves 28, Figs. 1, 4, and 5, in each of the conducting-tubes D is fitted to reciprocate vertically thereon a slide E, to the upper end of which is pivoted between side pieces c c a nail-pusher G, consisting of a main portion 30, having a narrow neck 31, extending inwardly and downwardly therefrom at an angle, as shown in Figs. 3, 5, 6, and 7, and provided at its end 15 with a head 32, which is adapted, when the slide E descends, to enter and pass through the enlargement 26 of the slot 25 after a nail-blank or partly-made nail has passed down the conductor into the position shown in 20 Fig. 3, with its lower or head portion in contact with the rolls B B.

33 is a flat spring secured to the lower end of the nail-pusher G, with its upper bent end bearing on the top of the slide E in such manner as to constantly exert an inward pressure on the pivoted nail-pusher, so that its head 32 will enter and pass through the opening 26 when brought into line therewith, the narrow neck 31 fitting the narrow portion of the 30 slot 25 and passing down through the same as the pusher is carried down by the slide E to bring its head 32 into contact with the upper end of the nail-blank, as shown in Fig. 3. On the ascent of the slide E the nail-pusher 35 is withdrawn from the tube D against the resistance of the spring 33 by the contact of the inner edge of the inclined neck 32 with the upper end 19 of the slot 25, on which it rides as it is drawn upward, the head 32 passing 40 out of the opening 26 and bearing against the outside of the conducting-tube D during the remainder of the upward movement of the slide, as shown in Fig. 4 and dotted in Fig. 3, thus leaving the interior of the tube D free 45 and clear for the passage of the next nail-blank to the rolls beneath.

The mechanism by which the slide E is reciprocated to produce the desired movements of the nail-pusher and cause the latter to exert a spring-pressure on the nail-blank when the latter is in contact with the rolls will now be described.

I is a horizontal shaft mounted in bearings in a bracket K, secured to the adjacent housing C. To this shaft is secured an arm 35, the inner end of which engages a slot 17 in the slide E, as shown in Figs. 6 and 7. To one end of the shaft I is secured a forked crank-arm 36, which is engaged by a pin 37 55 on a lever 38, fulcrumed at 39 on the bracket K, and provided at the end of its lower arm with a cam-roll 16, acted on by a cam 40 on the shaft 20, connected with one of the die-grooved rolls B, the roll being kept in contact 60 with the cam during the greater portion of its revolution by a spring 41, secured to the bracket K, and exerting a downward pres-

sure on the upper arm of the lever 38. As the cam revolves the outer end of the lever 38 is raised against the resistance of the 70 spring 41 and through the medium of the crank-arm 36, shaft I, and arm 35 raises the slide E into the position shown in Figs. 2 and 4, thus leaving the tube D clear for the passage of the blank or nail to the rolls B B 75 beneath. As soon as the blank or nail has dropped onto the rolls the cam 40 permits the spring 41 to depress the outer end of the lever 38, which through the connections described instantly depresses the slide E, causing the head 32 of the nail-pusher to pass into the conducting-tube D through the opening 26 and descend until it reaches the upper end of the blank or nail 18, upon which it will rest with a spring-pressure due to the action of 80 the spring 41, the cam in its revolution then passing for a short time entirely out of contact with the cam-roll 16, leaving said spring 85 41 free to exert its full force through the medium of the lever mechanism upon the nail-pusher, which in turn exerts a downward spring-pressure on the nail-blank during the time that the head-forming recesses 45 in the dies of the rolls B B are being brought around into a position to receive the lower end of the 90 blank to form the head of the nail. The moment that the recesses 45 of the dies reach the lower end of the blank it is instantly carried down to the bottom of said recesses by the strong spring-pressure of the nail-pusher 100 on its upper end, so that the blank is absolutely certain to reach its proper position in said dies without regard to the speed with which the rolls may be revolving. As the cam which controls the operation of the lever mechanism connected with the nail-pusher is secured to a shaft directly connected with the journal of one of the die-grooved rolls, it follows that the nail-pusher will always be ready 105 to act the moment that the head-forming recesses of the dies are in a position to receive the lower end of the blank. All liability of the dies failing to take the blank at the right moment is thus entirely avoided, and the formation of a head of the desired length is 110 thereby at all times insured. As the blank is drawn down between the rolls the nail-pusher is raised out of the tube D and the 115 operation continues as before.

The lever mechanism of the slide belonging to the next conducting-tube beneath or above is arranged at right angles to that just described, as shown in Figs. 1 and 2, and in this case the arm 35 engages a slot on the side of the slide E, as shown in Fig. 7, instead of one 125 in the front of the slide, as shown in Fig. 6.

What I claim as my invention, and desire to secure by Letters Patent, is—

1. In a nail-forging machine, the combination with a pair of die-grooved rolls and a nail-conducting tube or guideway leading thereto, of a reciprocating nail-pusher adapted to enter said tube after a nail or blank has been 130 dropped therein, and be subsequently with-

- drawn therefrom to permit of the passage of another blank or nail, mechanism for raising the nail-pusher and withdrawing the same from the conductor, and a spring acting on 5 said mechanism, whereby the nail-pusher is caused to descend, enter the conductor and exert a spring-pressure on the blank or nail therein to force the same into the dies of the rolls beneath, substantially as described.
- 10 2. In a nail-forging machine, the combination with a pair of die-grooved rolls and a nail-conducting tube or guideway leading thereto and provided with a longitudinal slot or opening, of a slide, a nail-pusher pivoted to said 15 slide and provided with a spring, whereby it is caused to enter the conductor as the slide descends, lever mechanism connected with said slide for raising the same, whereby the nail-pusher is withdrawn from the conductor, 20 and a spring acting on said lever mechanism to depress the slide, whereby the nail-pusher is caused to enter the conductor and exert a downward spring-pressure on the blank or nail therein to force the same into the dies of 25 the rolls beneath as soon as the latter are in a position to receive it, substantially as described.
3. In a nail-forging machine, the combination with a pair of die-grooved rolls, and a 30 slotted conducting tube or guideway leading thereto, of a slide movable longitudinally on said conducting-tube, a nail-pusher pivoted to said slide and provided with a spring exerting an inward pressure thereon, whereby 35 it is caused to enter said conductor as the slide descends, lever mechanism connected with said slide for raising the same and withdrawing the pusher from the conductor, and a spring acting on said lever mechanism for 40 depressing the slide and thereby causing the pusher when within the conductor to exert a downward spring-pressure on the blank or nail to force the same into the dies of the rolls beneath, substantially as described.
- 45 4. In a nail-forging machine, the combination with a pair of die-grooved rolls, and a conducting - tube leading thereto provided with a longitudinal slot or opening, of a slide 50 movable longitudinally on said conducting- tube, a nail-pusher pivoted to said slide and provided with a spring exerting an inward pressure thereon, whereby it is caused to enter the conductor as the slide descends, lever
- mechanism connected with said slide, a cam for actuating said lever mechanism in one direction to raise the slide, and a spring acting on said mechanism to produce a downward movement of the slide to cause the nail-pusher to enter the conductor and exert a spring-pressure on the blank or nail therein to force 60 the same into the dies of the rolls beneath, substantially as described. 55
5. In a nail-forging machine, the combination with a pair of die-grooved rolls, and a conducting - tube leading thereto provided with a longitudinal slot or opening, of a reciprocating slide, a nail-pusher pivoted to said slide and adapted to enter the conducting-tube and be withdrawn therefrom, a spring exerting an inward pressure on said nail-pusher, the latter having an inwardly-extending inclined or angular portion adapted as it rises to bear against the upper edge of the slot in the conducting-tube, whereby the pusher is withdrawn from said conducting - tube 70 against the resistance of its spring, substantially as described. 75
6. In a nail-forging machine, the combination with a pair of die-grooved rolls, and a conducting - tube leading thereto, said tube 80 having a longitudinal slot provided with an enlargement at its upper end, of a vertically-reciprocating nail - pusher provided with a spring exerting an inward pressure thereon, said nail-pusher consisting of a body portion 85 sliding on the outside of the conducting-tube, a narrow neck extending inward from the body portion at an angle thereto and adapted to slide within the narrow portion of the slot in the conducting-tube, and a head at the end 90 of said neck adapted to pass through the enlargement of said slot and exert a downward spring-pressure on the blank or nail in the conducting-tube, said angular neck portion by contact with the upper end of said slot, 95 causing the pusher as it is raised to be withdrawn from the conducting-tube against the resistance of its spring, substantially as described. 90

Witness my hand this 15th day of March, 100
A. D. 1900.

HENRY ALEXIS WILLIAMS.

In presence of—

P. E. TESCHEMACHER,
R. HENRY MARSH.
